CAN UNSCRAMBLER

Paul L. Alsup, Berkeley, Calif., assignor to F. E. Booth Company Inc., San Francisco, Calif., a corporation of Nevada

Application May 27, 1946, Serial No. 672,529

4 Claims. (Cl. 193—43)

1

The present invention relates to can unscramblers and particularly to devices for receiving cans delivered by a conveyor or chute in both inverted and upright positions and delivering the cans all in the same position to another conveyor or chute.

Some products, such as fish, are packed in relatively flat cans of the type which have the bottom and side walls drawn from a single piece of metal, and a top secured thereto by a seam. This construction produces a can which differs in appearance and shape at its top and bottom edges so that care is necessary, in applying labels and packing the cans in boxes, that all cans assume a right side up position. In practice the cans are packed and sealed and then placed in a retort for cooking of the contents. The cans are carried in large baskets in the retorts and are in scrambled or non-uniform positions in the baskets. After cooking, the baskets are removed from the retorts and their contents of cans are dumped onto a chute or conveyor by means of which they are directed toward processing machinery such for example as a label applying machine. Due to their scrambled condition, many of the cans occupy an inverted or upside down position on the conveyor. As it is desirable that all cans be directed to the labeler in the same position it is necessary that many of the cans, usually about half of them, be turned over.

It is an object of the present invention to provide a can unscrambler which through very simple and inexpensive mechanism will receive cans in either right side up or upside down position and without interrupting their usual travel toward a processing machine or the like will deliver them all in the same position. Further and more specific objects and advantages of the invention are made apparent in the following specification wherein, by reference to the accompanying drawings, the manner of attaining these objects is set forth in detail.

In the drawings:

Fig. 1 is a view in side elevation showing a can unscrambler which embodies the present invention;

Fig. 2 is a sectional view taken on the line II—II of Fig. 1;

Fig. 3 is an enlarged fragmentary perspective view of a portion of the can unscrambler illustrated in Fig. 1;

Figs. 4 and 5 are enlarged sectional views taken on the line IV—IV of Fig. 1 illustrating two positions which a can may assume in the unscrambler at this point; and

2

Fig. 6 is a section taken on the line VI—VI of Fig. 1 illustrating the position assumed by the can shown in Fig. 5 when it reaches this point.

Referring first to Fig. 1 of the drawings, the can unscrambler of the present invention is illustrated as disposed between spaced conveyor belts 10 and 11 to direct cans at a downward incline as they pass from the belt 10 to the belt 11, which is the direction of movement of cans on the conveyor system which includes these belts. The belts 10 and 11 are representative of any conventional conveyor or can directing means such as chutes or the like. Cans are delivered to the belt 10, or to some conveying means preceding it, in a scrambled condition as would result from their being dumped from a retort basket and are carried by said belt in a single file so that they may enter the upper end of the unscrambling apparatus one at a time.

20 The unscrambler receives all cans from the belt 10 without respect to their upright or inverted position and delivers them all in an upright position to the belt 11 by first compelling the cans to an on-edge position where they are unbalanced because of the seam which exists at their top edge only, and then permits them to fall by gravity. In Fig. 1 the can unscrambler is illustrated as comprising a can twister generally indicated at 12, an edge chute 13, and a transfer chute 14 by means of which the unscrambled cans are directed to the belt 11. The can twister 12 is conventional both as to its construction and function and may consist of any guide chute capable of receiving a can in a flat or horizontal position as it would be carried by the belt 10 and impelling it during its forward movement to twist about an axis parallel to the direction of its movement through approximately ninety degrees, or until it assumes an on-edge position. The twister herein illustrated comprises a horizontally disposed rectangular collar 16 arranged in a position to receive cans from the belt and a vertically disposed similar collar 17 through which the cans may be discharged. The collars 16 and 17 are spaced from each other and connected by any suitable guide chute capable of imparting a ninety degree twist to the cans as they pass through it. The chute herein shown is made of a plurality of bars 18 extending between the collars 16 and 17 and in this case preferably also extending a short distance beyond the collar 17 as shown at 19.

40 As the can leaves the twister 12 it is received in its on-edge position in the edge chute 13 which is of channel shaped cross section in order to support the can in an on-edge position as shown in

55

Figs. 4 and 5. Because the can is on-edge and because it is of the type which is provided with a seam 20 circumscribing its top edge while its bottom edge is without a seam and rounded as illustrated at 21, it tends to an inclined position where it is slightly unbalanced and disposed to fall to a position where it will rest on its bottom surface rather than on its top surface. This will be the case whether the can entered the twister in an inverted or an upright position because as it leaves the twister it will assume either a leftward tilt as indicated in Fig. 4 or a rightward tilt as indicated in Fig. 5. In order to impart a tilt to the can which is even greater than would be caused by its own shape, the channel shaped guide 13 is provided as best shown in Figs. 3, 4 and 5 with small bars or tracks 22 in each of its inside corners so that as the can slides on its edge through the channel the seam 16 will be compelled to ride on top of one of the tracks 22 whereas the curved portion 24 at its bottom edge will avoid the opposite track 22 as shown in Figs. 4 and 5. In this manner it is insured that the center of gravity of the can will be disposed in a position to compel it to fall toward its bottom side as it leaves the chute 13. A concave guide 23 is preferably although not necessarily disposed at the discharge end of the chute 13 and presents an upwardly facing smooth concave surface which receives the can approximately in the position illustrated in Fig. 6. This insures turning of the can by gravity to right side up position as it passes to the transfer chute 14 which, as shown in Fig. 6, is made up of a bottom slide plate 24 with fences or rails 25 secured to its opposite edges to confine the can to the slide plate as it travels toward the conveyor belt 11.

As the can leaves the twister 12 and enters the edge chute 13 its contact with the vertical edges of the channel shaped chute may retard its movement somewhat and tend to cause it to roll, particularly if it is the oval type can herein illustrated. The presence of the extended portions 19 of the bars 18 which make up the walls of the chute 12 however, and particularly the uppermost of said bars, will tend to prevent such rolling until the can assumes the position illustrated in either Figs. 4 or 5 and is ready to leave the end of the chute 13. The invention is not confined to the use of oval cans as it may be employed for unscrambling cans of rectangular or other shapes so long as they are of the drawn type which includes a seam at one edge which tends to cause the can to fall toward its bottom when it is supported in an on-edge position.

With the construction shown, cans carried by the conveyor 10 in scrambled condition will all enter the receiving end of the twister and will pass freely through the unscrambler at whatever speed they may be delivered to its receiving unit and will without fail be disposed in a right-side-up position on the conveyor 11. The tracks 22 disposed in the edge chute are desirable in most cases for imparting an increased tilt to the can which insures its falling in the right position even though its contents may be unevenly packed and its center of gravity may therefore be abnormal or unusually disposed. However, with the average can of the type herein shown, the invention will operate satisfactorily without the tracks 22.

While the unscrambler herein illustrated is operated entirely by gravity by virtue of its inclined arrangement, it is apparent that it may be otherwise arranged and that some means may be employed for impelling the can through the twister and edge chute if the present simple arrangement is not employed.

I claim:

1. A can unscrambler for cans having a seam on one edge only comprising a chute through which cans may slide on a seamed and unseamed edge, means engaging and elevating the seamed edge as the cans slide whereby they will be inclined to fall in a direction away from the seamed edge, and a concave plate to support the sliding cans as they leave the chute and as they fall in the direction they were inclined.
2. A can unscrambler for cans having a seam on one edge only comprising a chute through which cans may slide on a seamed and unseamed edge whereby they will be inclined to fall in a direction away from the seamed edge, and an arcuate guide receiving the inclined cans to permit them to fall in the inclined direction, said chute comprising a member of channel shaped cross section having a raised track in each corner and being of a width to confine the cans to a position with the seamed edge sliding on one of said tracks.
3. A can unscrambler for cans having a seam on one edge only comprising a chute through which cans may slide on a seamed and unseamed edge whereby they will be inclined to fall in a direction away from the seamed edge, and means to receive cans from the chute and support them for sliding movement as they fall, said chute including a portion of channel shaped cross section and tracks disposed in opposite corners of the chute in a position to engage and elevate the seamed edge of the can while permitting its unseamed edge to slide on the bottom of the chute.
4. A can unscrambler for cans having a seam on one edge only comprising a chute through which cans may slide on a seamed and unseamed edge whereby they will be inclined to fall in a direction away from the seamed edge, said chute including a portion of channel shaped cross section and tracks disposed in opposite corners of said portion in a position to engage and elevate the seamed edge of the can while permitting its unseamed edge to slide on the bottom of the chute, and a concave track adjacent the discharge end of the chute to support the cans as they fall.
